CLAIM

The ornamental design for a releasable clip for holding sheets of paper together, as shown and described.

DESCRIPTION

FIG. 1 is an inside plan view of a releasable clip for holding sheets of paper together, in an opened out state;

FIG. 2 is a plan view of the opposite side thereof;

FIG. 3 is a top plan view thereof;

FIG. 4 is a bottom plan view thereof;

FIG. 5 is a right side view thereof;

FIG. 6 is a left side view thereof;

FIG. 7 is a front plan view thereof in a closed state; and,

FIG. 8 is a left side view thereof.
